UNITED STATES PATENT OFFICE.

IRVING W. BLANCHARD, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR FORMING UPPERS OF BOOTS AND SHOES.

1,148,744.

Specification of Letters Patent. Patented Aug. 3, 1915.

Application filed November 21, 1914. Serial No. 873,395.

To all whom it may concern:

Be it known that I, IRVING W. BLANCHARD, a citizen of the United States, residing at Beverly, in the county of Essex and State 5 of Massachusetts, have invented certain Improvements in Machines for Forming Uppers of Boots and Shoes, of which the following description, in connection with the accompanying drawings, is a specification, 10 like reference characters on the drawings indicating like parts in the several figures.

This invention relates to machines used in the manufacture of boots and shoes for the purpose of forming the upper materials, or 15 portions thereof, in substantially the shape desired for the finished shoe before the upper has been brought into assembled relation to the materials that constitute the bottom portions of the shoe. Machines of this 20 class are applicable to the manufacture of shoes of different types, but find their principal use at the present time in the manufacture of "stitch-down" shoes, in which the upper is provided with an out-turned 25 flange to receive the stitches or other fastenings by which the upper is secured to the sole. Such machines are disclosed, for example, in United States Letters Patent No. 998,682, granted to Karl Engel July 25, 30 1911, and in the pending application of Karl Engel and Louis M. Brown, Serial No. 464,559, filed Nov. 27, 1908.

The respective machines described in the patent and the application above mentioned 35 include, among other features, means for shaping the forepart of the upper, and according to the practice therein disclosed the marginal portion of the upper at the toe end is confined between members that impart 40 the necessary pressure to form the out-turned flange, and while the margin is thus subjected to pressure the unconfined portion of the blank is operated upon by a toe former which imparts to the blank the shape 45 desired for the forepart of the vamp in the finished shoe. This toe forming operation obviously requires a fullness of that portion of the material bounded by the clamped margin, and by reason of the variation in 50 contour at different parts of the toe of the shoe, there will be a corresponding variation in the amount of material required for shaping different portions. In order to avoid unduly straining or tearing the blank, 55 therefore, it is necessary to provide for some

distribution of the material to meet the demands of the operation of the toe former. The machines disclosed in the patent and the application above mentioned accordingly have provision for suitable compensating 60 movement of the flange portion of the upper materials, which is effected by providing clamp members with portions that are movable substantially in the plane of the clamped margin of the blank to guide and 65 impart to the different portions of the blank at the margin movements in suitable directions and of sufficient extent to meet substantially the demands of the toe former and insure the formation of a smooth toe without 70 subjecting any portion of the material to excessive strains.

This invention, in its more particular aspect, relates to apparatus for shaping the forepart or toe portion of shoe uppers, and 75 especially to mechanism such as referred to above for guiding and imparting to the clamped marginal portion of the blank the requisite compensating movement.

An object is to effect improvements in 80 mechanism hitherto employed or proposed for this purpose, and to insure positive control and suitable movement of the blank margin to produce a smooth and well formed toe of the desired shape.

The several features of the invention, including certain details of construction and combination of parts, will now be described with reference to the accompanying drawings and pointed out in the claims.

The invention is illustrated as embodied in mechanism suitable for use as part of the machine shown and described in the pending application above referred to, only such portions of the machine being shown herein as 95 are necessary for an understanding of the present invention. It will be understood, however, that with obvious changes the mechanism shown may be adapted for use in apparatus such as illustrated in the above 100 mentioned patent to Karl Engel, or in other machines or apparatus of the like general class.

In the drawings, Figure 1 is a perspective view, with portions broken away, of apparatus in which the invention is embodied; Fig. 2 is a plan view of a portion of the apparatus shown in Fig. 1 with parts removed; Fig. 3 is a plan view with portions removed and other portions broken away,

showing the positions assumed by parts of the apparatus at the end of an operation upon a blank; Fig. 4 is a vertical section on the line 4-4 of Fig. 3 and Figs. 5 and 6 show detached parts in detail.

The means for confining and operating upon the marginal portion of the blank comprises coöperating relatively movable clamp members of which the member 2, shown 10 partly by dotted lines in Fig. 1, is formed with a smooth face to engage the upper or finished side of the material and is arranged for movement in a well known manner toward and from clamping position with reference to the coöperating clamp member, to be described, which is arranged to engage the margin of the material upon its lower or unfinished surface. The lower clamp member includes a base 4 constructed for attachment 20 to the machine in suitable coöperative relation to the upper clamp member 2 and supporting a plate 6 which is mounted for sliding movement forwardly and backwardly thereon. Overlying a portion of the plate 6 and retained in position by headed bolts 8 which are secured to the base 4 is a plate 10, one function of which is to assist in retaining and guiding the plate 6 for sliding movement in a predetermined path upon the base 4. The member 6 is slotted at 12 to receive the bolts 8, and has secured upon its opposite sides bars 14 which overlap the edges of the plate 10 and thus serve as additional means to guide the member in its 30 movements. The member 6 is moved rearwardly and retained normally in its rearmost position by springs 16, the ends of which are connected respectively to said member and to the base 4, and is moved forwardly by mechanism which it is unnecessary for an understanding of the present invention to describe in detail, but including pushers 18 carried by a bar 20, the construction and operative relation of these parts to 40 other portions of the machine being more fully disclosed in the pending application previously referred to.

In the upper surface of the plate 6 are formed a series of slots 22 which are arranged to converge toward the body of the blank to be operated upon and extend outwardly in divergent directions toward the outer edges of the plate. The central or foremost slot of the series, as shown clearly 50 in Fig. 2, extends in parallel relation to the line of movement of the member 6, and in this slot is mounted a bar 24 provided with teeth for engaging and positioning the margin of the toe blank at its front end. The 55 plate 10 is provided with a pin 26 which enters a socket in the bar 24 and serves to retain the bar in a stationary position irrespective of movement of the member 6. In the other slots 22, which are disposed in 60 angular relation to the line of movement

of the member 6, are mounted a series of slides 28 which are likewise provided with teeth for engagement with the margin of the blank and are similar in form one to another except that the two rearmost slides 70 which engage the blank at locations most remote from the front end are wider than the others to enable them to secure a more effective hold upon the material. By reason of the arrangement of the slots 22 the member 75 6 thus provides wedge shaped portions 34 which separate the several slides from one another and also the bar 24 from the slides which are adjacent thereto. Each of the slides 28 is provided also with a projection 80 30 which enters a slot 32 in the stationary plate 10, this slot, as shown in Fig. 3, being curved to conform substantially to the contour of the edge of the toe blank.

From the above description it will be evident that the plate 6, which serves to support the slides 28 as well as the bar 24, will, upon movement thereof, impart simultaneously to the several slides movements which will be controlled by the engagement of the 90 projections 30 in the slot 32 of the plate 10. The tendency of the member 6 is to carry the several slides forwardly with it, but the slot 32 directs and to some extent prevents such forward movement, causing the slides to 95 travel in a path conforming substantially to the contour of the edge of the blank. It will be apparent that the slides which are adjacent to the stationary bar 24 at opposite sides thereof have the smallest component of 100 forward movement but are crowded over toward the bar by the action of the wedge shaped members 34 and thus serve to gather the material at the margin of the blank at opposite sides of the bar. Similar gathering 105 movement of the material takes place between the members of each pair of adjacent slides; and since the slides are spaced at substantially equal distances from one another after, as well as before, the forward 110 movement of their supporting member 6, as shown by comparison of Figs. 1 and 3, it will be understood that the material is gathered uniformly along the margin, and that each slide moves a greater distance and 115 therefore faster than the slide which is immediately in advance thereof. The material at the sides of the blank is thus moved forwardly and inwardly toward the toe end simultaneously with the gathering of the 120 material along the margin, thereby providing the requisite amount of fullness in the blank to permit the formation of a smooth toe by the operation of the toe former 36.

The operation of the described mechanism 125 takes place after a blank which is to be molded in the form of a toe with an out-turned flange has been adjusted and clamped at its margin between the coöperating clamp members. The toe former 36 is then 130

raised and together with the carrier 20 is moved forwardly to shape the toe. During this forward movement the plate 6 also is advanced by the pushers 18 and causes movement of all the slides 28 simultaneously in the manner previously described, thereby effecting with accuracy and precision such gathering and compensating movement of portions of the blank as to meet the demands of the toe former and permit the formation of a smoothly shaped toe without excessive strain upon the material. After these operations the different parts of the mechanism are retained in the toe shaping relation illustrated in Figs. 3 and 4 a sufficient time to permit the materials to set in the form in which they have been molded. The toe former and the carrier 20 are then retracted and the clamp members separated so as to release the work, thereby permitting the plate 6 and the slides to be returned by the springs 16 to the positions indicated in Fig. 1.

Although the invention has been described as embodied in mechanism in which the slides have their operative movement simultaneously with the operative movement of the toe former, it should be understood that in the broader aspects of the invention it is immaterial at what particular time the compensating movement is imparted to the marginal portion of the materials and that provision for the operation of the slides before the operation of the toe former is within the scope of the invention.

The term "blank" or "toe blank" used in the claims is to be understood as referring generally to the materials which are to be operated upon, such, for example, as the forepart of an assembled shoe upper; such materials being suitably shaped for use in forming the toe of a shoe, or other like article of manufacture.

Having described the invention, what I claim as new and desire to secure by Letters Patent of the United States is:—

1. In apparatus for shaping a toe blank, a plurality of movable members arranged to engage the blank in a series along the margin thereof, and means for moving said members toward the toe end of the blank, said means being constructed and arranged to impart movement to all of said members simultaneously and to move different members of the series different distances.

2. In apparatus for shaping a toe blank, a plurality of movable members arranged in a series and each having a portion formed to engage the margin of the blank, and means for moving said members in directions to carry their blank engaging portions toward the toe end of the blank, said means being constructed and arranged to impart movement to all of said members simultaneously and to move each of said members

a greater distance than the member located directly in front thereof.

3. In apparatus for shaping a toe blank, a plurality of movable members arranged to engage the blank in a series along the margin thereof, and operating means for said members constructed and arranged to move all of said members simultaneously toward the toe end of the blank and to shorten the distance between adjacent members of the series during said movement so as to gather the material at the margin of the blank.

4. In apparatus for shaping a toe blank, a plurality of movable members arranged to engage the blank in a series along the margin thereof, and means for moving all of said members simultaneously toward the toe end of the blank, said means being constructed and arranged to move each of said members faster than the member directly in front thereof so as to shorten the distance between adjacent members of the series during said movement.

5. In apparatus for shaping a toe blank, a plurality of movable members each having a portion formed to engage the margin of the blank, means for moving the different members simultaneously at respectively different rates of speed in the direction of the toe end of the blank, and means for guiding said members to direct the blank engaging portions thereof in a path forming a curve about the body of the blank.

6. In apparatus for shaping a toe blank, a plurality of movable members arranged to engage the blank in a series along the margin thereof, and operating means for said members constructed and arranged to engage each of said members individually and to move all of said members simultaneously in the direction of the toe end of the blank.

7. In apparatus for shaping a toe blank, a plurality of members formed to engage the marginal portion of the blank, a support upon which said members are mounted, the support and said members being relatively movable, means for moving the support forwardly, and means operative upon the forward movement of the support for causing relative movement between said members and the support.

8. In apparatus for shaping a toe blank, a plurality of members arranged to engage the blank in a series along the margin thereof, a support upon which said members are mounted, the members being movable relatively to the support and to one another, means for moving the support forwardly, and means constructed and arranged to cause relative approach of adjacent members of the series during the forward movement of the support.

9. In apparatus for shaping a toe blank, a plurality of slides arranged to engage the

blank in a series along the margin thereof, a forwardly movable support having slots in which the slides are mounted, said slots being formed to converge toward the body 5 of the toe blank, and means constructed and arranged to cause the slides to assume positions nearer the convergent ends of the slots upon the forward movement of the support.

10. In apparatus for shaping a toe blank, 10 a plurality of slides arranged to engage the blank in a series along the margin thereof, a forwardly movable support having slots in which the slides are mounted, said slots being formed to converge toward the body 15 of the toe blank, and controlling means constructed and arranged to cause the slides to move in a curved path forwardly toward the toe end of the blank and to assume positions nearer the convergent ends of the slots 20 upon the forward movement of the support.

11. In apparatus for shaping a toe blank, a plurality of slides arranged to engage the blank in a series along the margin thereof, a forwardly movable support for said slides 25 having wedge shaped portions arranged between the slides to impart movement thereto upon a movement of the support, and guiding means formed to direct the slides in a path conforming substantially to the contour of the blank margin during said movement thereof.

12. In apparatus for shaping a toe blank, 30 a plate arranged to underlie the marginal portion of the blank and having slots formed to extend outwardly in divergent directions under the blank margin, slides mounted in said slots and formed for engagement with the blank, said plate being forwardly movable, and means for controlling the slides to cause their blank engaging 35 portions to remain under the blank margin during said movement of the plate.

Copies of this patent may be obtained for five cents each, by addressing the "Commissioner of Patents.
Washington, D. C."

13. In apparatus for shaping a toe blank, a plate arranged to underlie the marginal portion of the blank and having slots 45 formed to extend outwardly in divergent directions under the blank margin, slides mounted in said slots and formed for engagement with the blank, said plate being forwardly movable, and a stationary member 50 arranged to engage the slides to cause relative movement between the slides and the plate upon the forward movement of the plate.

14. In apparatus for shaping a toe blank, 55 a plate arranged for rectilinear movement and having slots in its surface disposed in angular relation to the line of movement of the plate, slides in said slots formed to engage the margin of the blank, and a stationary controlling member arranged to engage the slides during the movement of the plate.

15. In apparatus for shaping a toe blank, 60 a plate arranged for rectilinear movement and having slots in its surface disposed in angular relation to the line of movement of the plate, slides in said slots formed to engage the margin of the blank, and a stationary controlling member above said plate 65 formed with a slot curved to conform substantially to the contour of the margin of the blank, the slides having projections extending within said slot to determine the path of movement of the slides during the 70 movements of the plate.

In testimony whereof I have signed my name to this specification in the presence of two subscribing witnesses.

IRVING W. BLANCHARD.
